US00D951378S

(12) **United States Design Patent** (10) **Patent No.:** **US D951,378 S**
Watry et al. (45) **Date of Patent:** **** May 10, 2022**

(54) **LOAD DISTRIBUTING GRIP HANDLE WITH LINE**

(71) Applicant: **Dynepic Sports, LLC**, Charleston, SC (US)

(72) Inventors: **Krissa Watry**, Charleston, SC (US); **Crystal M. Arn**, Sherwood, OR (US); **Cameron J. Arn**, Sherwood, OR (US); **Jason S. Arn**, Sherwood, OR (US)

(73) Assignee: **DYNEPIC SPORTS, LLC**, Charleston, SC (US)

(**) Term: **15 Years**

(21) Appl. No.: **29/749,083**

(22) Filed: **Sep. 2, 2020**

(51) **LOC (13) Cl.** **21-02**

(52) **U.S. Cl.**

USPC **D21/694**

(57) **CLAIM**

The ornamental design for a load distributing grip handle with line, as shown and described.

DESCRIPTION

FIG. 1 is an isometric view of the claimed load distributing grip handle with line, embodying the present design;

FIG. 2 is a front side view thereof;

FIG. 3 is a rear side view thereof;

FIG. 4 is a right side view thereof;

FIG. 5 is a left side view thereof;

FIG. 6 is a top down plan view thereof; and,

FIG. 7 is a bottom up plan view thereof.

The portions shown in broken lines in FIGS. 1-6 are not part of the claimed design but rather show the environment in which the design is associated.

1 Claim, 7 Drawing Sheets
